UNITED STATES PATENT OFFICE.

JOHN E. BELL, OF BROOKLYN, NEW YORK.

BOILER-BAFFLING.

1,257,302.

Specification of Letters Patent. Patented Feb. 26, 1918.

Continuation in part of application Serial No. 35,788, filed June 23, 1915. This application filed November 6, 1915. Serial No. 59,994.

To all whom it may concern:

Be it known that I, JOHN E. BELL, a citizen of the United States, residing at Brooklyn, in the county of Kings and State of New York, have invented a new and useful Improvement in Boiler-Baffling, of which the following is a full, clear, and exact description, reference being had to the accompanying drawings, forming part of this specification, in which—

Figure 1 is a sectional side elevation showing my invention applied to a boiler of the general Stirling type, and constructed in accordance with my co-pending application Serial No. 35,788, filed June 23, 1915.

Fig. 2 is a partial cross section showing a lower portion of the front baffle.

Fig. 3 is a partial cross section showing the baffling at the rear of the bank.

Fig. 4 is a partial longitudinal section of Fig. 3.

Figs. 5 and 6 are views similar to Figs. 3 and 4, showing a modification; and

Figs. 7, 8, 9 and 10 are partial cross sections showing modified forms of the baffling.

My invention relates to baffling for boilers and particularly to baffling overlying a row of tubes over which the heated gases flow, that is, tubes containing water or steam, or both.

In order to increase the amount of tube surface with which the hot gases may contact and thereby increase the economy and efficiency of the boiler, I provide baffling which is spaced apart from the tubes with which the baffling coats, thus increasing the heating surfaces and in many cases increasing the area of the pass for the gases. This is of especial importance in that portion of the boiler lying near the combustion chamber where the gases are of larger volume owing to their higher temperature.

In the drawings I show, in Fig. 1, a boiler of the general Stirling type in which the numerals 2, 3 and 4 represent the upper transverse steam and water drums, and 5 the lower transverse mud drum. These drums are connected by three banks of tubes 6, 7 and 8, the water spaces of the drums 3 and 4 being preferably connected by water circulators 9, and the three upper drums being preferably connected by steam circulating tubes 10 and 11 leading to the drum 3, from which the steam is preferably taken off through an outlet 12.

The furnace 13 is preferably shortened up so that the external arch 14 over it is short and can be properly stayed and cooled on its upper side, if desired. This furnace may, however, be extended outwardly to a greater extent if desired, particularly when burning hard coal.

At the rear of the furnace I show a reflecting bridge wall 15, and at the front of the front bank of tubes, I provide a baffle co-acting with the upper part of the bridge wall to form a contracted mixing throat or outlet 16 through which the flame and gases are led downwardly into the secondary combustion chamber 17. The upper portion 18 of this front baffle preferably lies on the back of the front row of tubes and the lower part, shown at 19, preferably incloses the tubes and may be of the type shown in Fig. 2. In this figure, the irregularly shaped blocks 20 are arranged in pairs with the thinner blocks 21 and are held by the refractory key members 22. The lower portion of this baffle should encircle those portions of the front row of tubes which lie along the contracted throat outlet of the furnace, to protect these tubes. These tiles are also preferably recessed to surround the band clamps on the water tubes which support the baffle, to protect these tubes from burning out. The upper rear portion of the bridge wall is preferably beveled or inclined into substantial parallelism with the baffle 19 to form the mixing throat through which the gases flow at relatively high velocity.

With this boiler, I show three baffles 24, 25 and 26 extending along the back of the three banks of tubes, the baffle 24 extending up from the mud drum and terminating short of the steam and water drum, and preferably provided with a rearwardly extending shelf 28 at its upper part. The baffle 25 extends downwardly from the drum 3 along the rear of the middle bank and terminates short of its lower end; while the baffle 26 covers a portion of the rear bank and holds the gases in this bank as they rise to the up-take 29.

In order to increase the area of flow space for the passage of the gases within the banks and to cause the gases to more thoroughly envelop the rear tubes of the banks, I space the baffling away from the rear tubes of the banks, as shown in Fig. 1. This is of especial importance in the first pass where

the gases are of larger volume, owing to their higher temperature. The heating surface is also increased in this bank as the gases are given access to portions of the tube surface which otherwise would be more or less covered by the baffling.

In Figs. 3 to 10, inclusive, I show different forms of this spaced apart baffling. In Figs. 3 and 4, the baffling tiles 30 have longitudinal depending leg portions 31 at one side, which portions rest on alternate tubes, the tiles each having a recessed beaded portion 32 over the leg portion and which is engaged by the thinner grooved portion 33 of the next tile. These tiles also preferably have a tongue and groove engagement at their ends, as shown at 34 in Fig. 4. The tiles may be of a width to span the space between two rows of tubes, as shown, or three or more rows, if desired.

In Figs. 5 and 6, I show a form similar to that of Figs. 3 and 4, except that each tile has along one edge an upwardly curved and recessed portion 35 having a tongue and groove engagement 36 with the next tile. These tiles preferably overlap each other at their ends, as shown at 37 in Fig. 6.

In Figs. 7 and 8 I show other modified forms in which the same numerals are used with the letters "a" and "b" applied, the overlapping projections being of different shapes, as shown.

In Fig. 9 the tiles take the form of channels 30^a, the legs 31^a fitting together and resting on a water tube.

In Fig. 10, I show the tiles 30^a as of transverse arch shape, arching from one tube of a row to a tube two or more rows distant therefrom. In this case, the end portions 31^a of adjacent arched tiles rest on the same water tube.

This type of baffling is used on the back of each bank and is also preferably used over the water circulators, as shown at 38, so as to allow the gases to envelop these water circulating tubes and thus further increase the heating surfaces.

It will be understood that this type of baffling may be used in many locations in a boiler. For example, they may be used as arch blocks lying on the water tubes in a locomotive boiler furnace; and they may overlie water or steam tubes in any part of a boiler.

In the boiler shown, the flame and gases rise from the furnace into the space in front of the front bank, the upper portions of the front row or rows of tubes being heated by radiant heat. They then flow, at highly increased velocity, downwardly through the throat between the bridge wall and the bank into the secondary combustion chamber, where practically complete combustion will occur. They then rise among the tubes of the front bank, sweeping over the tubes,

including the rear row of the tubes thereof and flow downwardly through the second bank, and up through the third bank. A high velocity is maintained through the front bank and, as heat transfer is more rapid at high temperatures, the effect of this increased velocity is more marked in the front bank.

On account of the mixing of the gases in the throat and the use of the secondary combustion chamber, the gases may be taken directly into the water heating surface. Taking the flame and gases directly into the lower water heating surface would otherwise be objectionable, since the gases would be chilled in their passage through the front bank and if combustion were not complete before entering that bank its further process would be stopped. The spaced apart baffling at the back of the front bank gives sufficient area through the front pass, which would otherwise be difficult to obtain.

The secondary combustion chamber back of the reflecting bridge wall is screened from the more intense radiation of the furnace and I preferably locate a superheater therein. This superheater may be located in the lower part of this combustion chamber as the eddies in the chamber will be sufficient to cause the gases to sweep over the surface. On account of the high temperature of these gases, a relatively small amount of superheating surface is required. Furthermore, on account of this location, the tubes of the superheater may be placed horizontally and supported at intervals throughout their length.

The superheater consists of two or more sets of tubes 39 extending between headers not shown at opposite ends and located in or outside the side walls, the headers being connected with suitable inlet and outlet pipes.

The superheater pipes may be supported on arches 40 spaced apart at intervals across the setting to support the pipes against warping or twisting out of shape.

The advantages of my invention result from the improved baffle tiling which adds to the amount of heating surface, gives larger flow space for the gases and thereby improves the economy and efficiency of the boiler.

Changes may be made in the form and arrangement of the tiles and their location on the water tubes, steam and water tubes, or steam tubes of a boiler without departing from my invention.

I claim:

1. A boiler having a row of tubes containing fluid to be heated, and a spaced-apart baffling coacting with said tubes, said baffling being composed of tiles having projections longitudinal of the tubes and resting on some of the tubes, and bridging over

other intermediate tubes, substantially as described.

2. A boiler having a row of tubes containing fluid to be heated, and a spaced-apart baffle coacting with the row of tubes and composed of refractory tiles, each tile having one side portion overlapping and resting upon the next tile and the other side portion provided with a projection extending longitudinally of a tube and resting thereon, the tiles bridging some of the intermediate tubes, substantially as described.

3. A boiler having a row of tubes containing fluid to be heated, and a continuous baffle supported on said row and spaced apart therefrom, the said baffle being arranged to cause the gases to flow longitudinally of and around the row and being composed of tiles which rest on some of the tubes

and bridge over other intermediate tubes, 20 substantially as described.

4. In a water tube boiler, a bank of tubes, and a continuous baffle at the rear of the bank and spaced apart therefrom, said baffle being supported on the row of tubes in front 25 of it and extending from one end of the row to a point short of the other end to cause the gases to flow longitudinally within the bank, said baffle resting upon part only of the tubes and bridging other tubes of the 30 row, substantially as described.

In testimony whereof I have hereunto set my hand.

JOHN E. BELL.

Witnesses:

JOHN PRIMROSE,
FRANK PAGE.
